SQUIRTING PRESS FOR THERMOPLASTIC
MASSESEmil Hempel, Zerbst, Germany; vested in the
Alien Property CustodianApplication June 20, 1936, Serial No. 86,402
In Germany June 29, 1935

16 Claims. (Cl. 18—30)

This invention relates to machines for injecting thermoplastic masses into moulds.

When squirming thermoplastic masses, e. g. certain artificial resins, the accurate fixing of the most favourable operating conditions is important. These depend for example on the size of the moulded articles, the cross-section of the squirming nozzle or the pressure of the squirming machine. It is advisable to determine the most favourable conditions from case to case by experiment and subsequently regulate the squirming machine.

The present invention consists in a machine which itself takes over the task of producing the correct operating conditions. In order to prevent the working material from being squirted out too quickly and to allow sufficient time for heating the squirted material so that it will be sufficiently plastic, a pressure gauge is connected up to the squirming piston, the said pressure gauge adjusting a preferably hydraulic brake connected to the driving piston, according to the resistance of the squirted substance, when the resistance for any reason exceeds the maximum pressure permissible for the moulded article, which has been previously determined by experiment and for which the adjustment has been effected. In this manner, the operating speed of the squirming piston is reduced from a selected squirming pressure by retarding the forward movement of the driving piston to correspond to the resistance. It is thus ensured that the squirming of the mass will be effected in a regulated manner, one object of which is to provide for sufficient heating of the mass. This is for instance attained by a weight-loaded wedge slide which is adjusted by the pressure fluid of a measuring gauge fitted in the squirming piston, proportionately to the pressure in the measuring gauge, the said wedge slide in turn adjusting a control valve in the circulation pipe of the hydraulic brake in such a manner that the cross section of the opening through the valve is correspondingly reduced, if need be until the valve is fully closed. The action of the wedge slide can be adjusted, in the first place by varying the loading weight acting against the pressure of the fluid in the measuring gauge and then by varying the leverage with which the loading weight acts. More particularly, the counterweight may be suspended from a snail plate which is adjustable relatively to the wedge slide.

The hydraulic brake for regulating the operating speed of the driving piston is, in accordance with the invention, connected up to a sec-

ond hydraulic brake, which comes into action during the return stroke of the driving piston, at the end of the stroke, in that it reduces the velocity of the return movement of the driving piston at the end of the return stroke, whereby the driving piston is prevented from coming to a stop with a blow at the end of the return stroke.

For obtaining the same effect as the features 10 above referred to, namely the automatic production of the correct operative conditions by the machine, a new form of drive is provided. This new form of drive is characterised by the feature that a toggle is interposed between the driving 15 piston and the press or squirming piston, which depresses the squirming piston rapidly at the commencement of the forward movement of the driving piston and later in the course the forward movement of the driving piston depresses the 20 squirming piston more slowly.

It is known to drive such machines on the one hand hydraulically or pneumatically by means of a press piston movable in a cylinder or by means of a toggle actuated by a crank. In the case 25 where the drive is effected by means of a pressure medium, however, a toggle has not hitherto been interposed because its use has not been considered necessary. The pressure of the pressure fluid has simply been allowed to act directly to 30 a sufficient extent to enable the necessary press pressure to be obtained. By this means, however, when the thermoplastic mass is very viscous, very considerable pressures are developed, so that compressors or compressing pumps operating at 35 very high pressures are necessary and the supply piping to the squirming machine has to be constructed to withstand very high pressures. This results not only in the manufacturing costs of the machine plant being considerably higher 40 but also in the operation and maintenance of the machine being rendered difficult. Should leakage occur, then such leakage is more troublesome the higher the pressure is. In contradistinction thereto, the driving piston in the arrangement according to the invention can be operated with a pressure fluid at a comparatively 45 low pressure. A few atmospheres suffice because the toggle produces the necessary pressure step up. The toggle, however, is an exceedingly simple machine element which is easily kept in repair and cheap, its interposition between the pressure fluid piston and the squirming piston reducing the cost of the entire plant, simplifying its operation and rendering it reliable. All these 50 advantages disappear if the machines are oper-

ated with crank drive and toggle, even though the pressure step up per se is also present.

In addition to these advantages, the provision of the toggle has the advantage that the squirming pressure is greatest when the squirming is taking place. The mass which has been charged into the press cylinder is at the outset granular and loosely layered and passes into a viscous state under the influence of the pressure and heat which is supplied from the outside; while the mass is still granular, a lower pressure suffices, if only to avoid premature extrusion of the mass out of the press cylinder into the mould. On the other hand, when the mass has become viscous under the pressure and heating and has now in fact to be expelled, a very much greater pressure is required. This requirement is attended to by the toggle itself.

Finally, the invention comprises a special construction of toggle mechanism in which the guide lever of the toggle is pivoted on a swinging lever which by means of a linkage transmits the force acting on the guide rod of the toggle to the mould with a considerable step up. By this means the advantage is obtained that the peak pressure exerted by the toggle is utilised at the same time to maintain the mould closed, the pressure required for maintaining the mould closed being always greater than the pressure exerted by the contents of the mould which tends to open the mould.

A constructional example of a squirming machine according to the invention is illustrated in the drawings, in which

Fig. 1 is a side elevation of the machine, partly in section,

Fig. 2 is a vertical section of the squirming piston with the guiding means and actuating mechanism,

Fig. 3 is a side elevation of the parts shown in Fig. 2.

Referring to the drawings, it is pointed out at the outset that the braking mechanism of the driving piston and its loading weights are shown in alternative positions in Figs. 1, 2 and 3. This is in order to render the illustration clear. In practice, each of the three alternative positions of these parts shown in the individual figures is possible. All the three representations of these parts agree in form and the number of their members with one another.

The squirming piston 2 is movable vertically in a guide 3 on the machine frame 1. Below the squirming piston lies the two-part mould 4. The cylinder 5, for instance a compressed air cylinder, serves for the drive of the squirming piston, a piston 6 being slidable in the said cylinder, the said piston in the illustrated example being constructed as a differential piston, the larger side of which produces the working pressure and the smaller side serves for returning the working and squirming pistons. The piston 6 is connected up by means of a rod 7 to the joint 8 of a toggle comprising a guide lever 9 and a press lever 10 which is connected up by means of a pivot 11 to the squirming piston 2, while the guide lever 9 is connected up by means of a pivot 12 to the machine frame. The pivot 12 is not mounted directly and immovably on the machine frame but is displaceable between limits for the purpose hereinafter explained.

Below the squirming piston 2 is located a container 13 for receiving the squirted material and into which the lower end of the squirming piston extends. The container 13 has an outlet 15

which as shown in Fig. 1 rests directly upon the squirming mould, the bore of the container forming a continuation of a bore in the squirming mould.

5. Laterally of the container 13 is located a filling device 16 for the squirted material which is supplied from the filling device by means of a measuring roller 17 to the filling cylinder 13.

The mould 4 rests upon a platform 18 which 10 can be raised and lowered through the intermediary of a screw spindle 19, a nut 20 and toothed reduction gearing 21 by a small electric motor which is automatically switched on and off by means of contacts controlled by the machine. 15 In this manner the motor can close and open the mould.

The squirming piston, as shown in Fig. 2, is constructed in two parts, comprising a sleeve 23 and a squirming piston proper 24 which is axially 20 slidable in this sleeve. The piston 24 is packed with respect to the sleeve 23 at 25 and 26 and the hollow space 27 above the piston 24 is filled with oil, a flexible pipe 28 leading from the hollow space 27 to the control means for adjusting the 25 piston velocity.

The said control means comprises a small piston 29 which extends into the tube 28 and is rigidly connected to a wedge slide 30, which is in part provided with gear teeth which engage in a gear wheel 31, on the spindle 32 of which a snail plate 33 is fixed. Around the snail plate 33, which is enclosed in a casing 34, is passed a tension member, e. g. a chain 35 on which hangs a composite weight 36 serving for maintaining 35 the pressure of the liquid from the space 27 acting on the small piston 29 of the weighing device. The opposing pressure acting on the piston 29 can be varied by adjusting the snail plate 33 relatively to the gear wheel 31, which is connected to the spindle 32 by means of a coupling 37, which can be opened and closed by means of a hand wheel 38. When the coupling is opened the gear wheel 31 and the snail plate 33 can be turned relatively to one another. In this manner 45 the lever arm at which the weight 36 acts can be varied.

A brake piston 39 is connected to the working piston 6, the said brake piston being slidable in two cylinders 40 and 41. The cylinder 40 serves 50 as brake cylinder during the working stroke, while the cylinder 41 serves as brake cylinder at the end of the return stroke. Both cylinders are filled with oil. To the cylinder 40 belongs a circulating pipe 42 in which a valve 43 is interposed, the valve body 44 of which rests upon the wedge surface 45 of the wedge slide 30. The position of the valve body 44 varies according to the 55 position of the slide 30 and with it the braking resistance which the oil, forced by the piston 39 through the circulating pipe 42, exerts upon the working piston 6. A second circulating pipe 46 with a brake valve 47 belongs to the cylinder 41. The valve 47 produces the braking pressure during the return of the piston 6.

65 It has already been mentioned that the lower pivot 12 of the guide lever 9 does not have a fixed location, the lever on the contrary being pivoted on a two-armed lever 48 which is capable of rocking about a fixed fulcrum 49 on the machine. The free end of the lever 48 rests upon a pressure rod 51 which bears against a one-armed lever 52 capable of rocking about a fulcrum socket 53 in the machine frame, the lever 70 also bearing with its back 54 upon a sleeve 55 resting upon the top of the mould 4.

The mode of operation of the machine described is as follows:

After the mould 4 has been inserted and closed by means of the motor 22 and the spindle 18, the container 13 is filled with material to be squirted. A pressure medium, e. g. compressed air is then admitted to the cylinder 6, whereupon the piston 2 is forced downwardly through the intermediary of the toggle 9, 10. By this means, the plastic mass 14, which is heated by any suitable means, is compressed and finally forced through the bore of the outlet 15 into the press mould 4.

Under the reaction pressure of the inner part 24 of the squirting piston 2 acting on the fluid in the space 27, fluid is forced out of this space into the pipe 28. This fluid in turn exerts pressure upon the piston 29 and the latter displaces the wedge slide 30 outwardly against the load produced by the weight 36. By this means, the weight 36 is always adjusted into a new position of equilibrium according to the resistance of the plastic mass and the opposing pressure of the weight 36 which is varied by the snail plate 33, that is to say, as the resistance rises, the further movement of the toggle causes the valve body 44 of the oil brake of the driving piston 6 to rise, thereby gradually increasing the oil resistance in the circulation pipe 42, so that as the resistance of the squirted material rises the working piston 6 moves progressively more slowly. This is important in order to give the viscous plastic mass time to flow out into the mould and thereby prevent overloading of the machine.

On the return stroke of the working piston 6, the oil brake 39, 41 comes into action and absorbs any blow which might be set up during the return travel of the piston. The length of the cylinders 40 and 41 determines the times when the oil brake comes into action during the forward and return movements of the working piston 6.

When the toggle 9, 10, increases the press pressure acting on the squirted material, then the force with which the guide rod 9 of the toggle acts upon the two-armed lever 48 and consequently also the pressure of the rod 51 acting on the one-armed lever 54 also increases. The lengths of the levers 48 and 52 are so proportioned that the closure pressure of the squirting mould is always greater than the opening pressure which the plastic mass injected into the mould exerts outwardly on the mould. In this manner, the mould is always held closed. On the other hand, it is automatically relieved of load when the toggle is drawn back.

What I claim is:

1. In a machine for squirting thermoplastic masses, in combination a driving piston, a squirting piston operatively connected to said driving piston for actuation by the driving piston, a brake operatively connected to the driving piston for retarding the motion of the driving piston during the working stroke and adjusting means for said brake including a pressure-responsive device connected to the squirting piston for adjusting the braking resistance, so as to increase the braking resistance as the squirting resistance rises and retard the forward movement of the driving piston and squirting pistons to correspond to the increasing resistance set up by the thermoplastic mass as the squirting progresses.

2. In a machine for squirting thermoplastic masses, in combination a driving piston, a squirting piston operatively connected to said driving piston for actuation by the driving piston, a fluid

5 pressure brake operatively connected to the driving piston for retarding the motion of the driving piston during the working stroke and adjusting means for said brake including a pressure-responsive device connected to the squirting piston for adjusting the braking resistance, so as to increase the braking resistance as the squirting resistance rises and retard the forward movement of the driving piston and squirting pistons to correspond to the increasing resistance set up by the thermoplastic mass as the squirting progresses.

3. In a machine for squirting thermoplastic masses, in combination a driving piston, a squirting piston operatively connected to said driving piston for actuation by the driving piston, a fluid pressure brake operatively connected to the driving piston for retarding the motion of the driving piston during the working stroke, a circulation pipe for said brake having a control valve therein for permitting the escape of fluid into the circulation pipe to reduce the braking action, adjusting means for said valve including a wedge slide and a pressure responsive device connected 10 to the squirting piston and to the wedge slide for displacing the wedge slide and moving the valve into the closing position as the squirting resistance rises, so as to increase the braking resistance and retard the forward movement of the driving and working pistons to correspond to the increasing resistance set up by the thermoplastic mass as the squirting progresses, and a counterweight operatively connected to the wedge slide and arranged to act in opposition to the 15 adjusting means.

4. In a machine for squirting thermoplastic masses, in combination a driving piston, a squirting piston comprising a hollow outer member operatively connected to said driving piston for actuation by the latter and an inner member 20 slidably in the outer member and arranged to protrude from the outer member so as to act on the mass to be squirted, the end of the outer member remote from the protruding end of the inner member being closed so as to form a space above the end of the inner member for containing pressure fluid, a brake arranged for operation by pressure fluid and operatively connected to the driving piston for retarding the motion of the driving piston during the working stroke and adjusting means for said brake comprising a vent valve for permitting the escape of fluid from the brake, a wedge slide operatively connected to the vent valve, adjusting means 25 arranged for operation by fluid pressure for adjusting the wedge slide and a flexible pipe connected to said space and said adjusting means for displacing the wedge slide and moving the valve into the closing position as the squirting pressure increases the pressure of the fluid in the said space and a counterweight operatively connected to the wedge slide and arranged to act in opposition to the adjusting means.

5. In a machine for squirting thermoplastic masses, in combination a driving piston, a squirting piston comprising a hollow outer member connected to the driving piston for actuation by the latter and an inner member slidably in the outer member and arranged to protrude from one end of the outer member so as to act on the mass to be squirted, the other end of the outer member being closed so as to form a space above the end of the inner member for containing a pressure fluid, a brake operatively connected to the driving piston for retarding the motion of

the driving piston during the working stroke, fluid-operated adjusting means for varying the braking resistance, a conduit connected to said adjusting means and to the said space in the outer member of the squiring piston for transmitting the fluid pressure in said space to the adjusting means so as to actuate the adjusting means to increase the braking resistance as the squiring resistance rises and retard the forward movement of the driving and squiring pistons to correspond to the increasing resistance set up by the thermoplastic mass as the squiring progresses.

6. In a machine for squiring thermoplastic masses, in combination a driving piston, a squiring piston comprising a hollow outer member connected to the driving piston for actuation by the latter and an inner member slideable in the outer member and arranged to protrude from one end of the outer member so as to act on the mass to be squirted, the other end of the outer member being closed so as to form a space above the end of the inner member for containing a pressure fluid, a fluid pressure brake operatively connected to the driving piston for retarding the motion of the driving piston during the working stroke, fluid-operated adjusting means for varying the braking resistance including a venting valve, a conduit connected to said adjusting means and to the said space in the outer member of the squiring piston for transmitting the fluid pressure in said space to the adjusting means so as to actuate the adjusting means to increase the braking resistance as the squiring resistance rises and retard the forward movement of the driving and squiring pistons to correspond to the increasing resistance set up by the thermoplastic mass as the squiring progresses.

7. In a machine for squiring thermoplastic masses, in combination a driving piston, a squiring piston comprising a hollow outer member connected to the driving piston for actuation by the latter and an inner member slideable in the outer member and arranged to protrude from one end of the outer member so as to act on the mass to be squirted, the other end of the outer member being closed so as to form a space above the end of the inner member for containing a pressure fluid, a fluid-pressure brake operatively connected to the driving piston for retarding the motion of the driving piston during the working stroke, a circulation pipe for said brake having a control valve therein for permitting the escape of fluid into the circulation pipe to reduce the braking action, a wedge slide operatively connected to said valve, fluid-operated adjusting means for said wedge slide and a flexible pipe connected to the said space and said adjusting means for displacing the wedge slide and moving the valve into the closing position as the squiring pressure increases the pressure in the said space.

8. In a machine for squiring thermoplastic masses, the combination as set forth in claim 3 with a snail plate having a spiral track thereon and a tension member passed around said spiral track for supporting the counterweight so as to increase the force exerted by the counterweight on the adjusting means as the wedge slide is displaced to move the valve towards the closing position.

9. In a machine for squiring thermoplastic masses, the combination as set forth in claim 3 with a shaft having a snail plate and a gear wheel thereon and adjustable angularly one with

respect to the other, the wedge slide having gear teeth thereon meshing with the said gear wheel.

10. In a machine for squiring thermoplastic masses, the combination as set forth in claim 1 with a hydraulic brake operatively connected to the driving piston for braking the latter at the end of its return movement.

11. In a machine for squiring thermoplastic masses, in combination, a compressed air operated driving piston, a squiring piston, a toggle interposed between said driving and squiring pistons for establishing a driving connection between them, the linkage of said toggle being arranged to transmit the motion of the driving piston so that the squiring piston travels forward quickly at the commencement of the forward motion of the driving piston but slows down as the said forward motion progresses, a mould, a rocker lever, a guide lever for the toggle pivoted on the rocker lever, said rocker lever operatively connected to the mould so as to transmit the tension acting in the guide lever to the mould as a compressive force for maintaining the mould closed during the squiring operation.

12. In a machine for squiring thermoplastic masses, in combination, a compressed air operated driving piston, a squiring piston, a toggle interposed between said driving and squiring pistons for establishing a driving connection between them, the linkage of said toggle being arranged to transmit the motion of the driving piston so that the squiring piston travels forward quickly at the commencement of the forward motion of the driving piston but slows down as the said forward motion progresses, a mould, a rocker lever, a guide lever for the toggle pivoted on the rocker lever and a closing lever arranged to bear on the mould and operatively connected to the rocker lever, said closing lever having its fulcrum so located that it transmits the tension acting in the guide lever to the mould as a magnified compressive force for maintaining the mould closed during the squiring operation.

13. In a machine for squiring thermoplastic masses, in combination a driving piston, a squiring piston operatively connected to said driving piston for actuation by the driving piston, a fluid pressure brake operatively connected to the driving piston for retarding the motion of the driving piston during the working stroke, a circulation pipe for said brake having a control valve therein for permitting the escape of fluid into the circulation pipe to reduce the braking action, adjusting means for said valve including a wedge slide and a pressure responsive device connected to the squiring piston and to the wedge slide for displacing the wedge slide and moving the valve into the closing position as the squiring resistance rises, so as to increase the braking resistance and retard the forward movement of the driving and working pistons to correspond to the increasing resistance set up by the thermoplastic mass as the squiring progresses.

14. In a machine for squiring thermoplastic masses, in combination a driving piston, a squiring piston comprising a hollow outer member operatively connected to said driving piston for actuation by the latter and an inner member slideable in the outer member and arranged to protrude from the outer member so as to act on the mass to be squirted, the end of the outer member remote from the protruding end of the inner member being closed so as to form a space above the end of the inner member for containing pressure fluid, a brake arranged for operation by

pressure fluid and operatively connected to the driving piston for retarding the motion of the driving piston during the working stroke and adjusting means for said brake comprising a vent valve for permitting the escape of fluid from the brake, a wedge slide operatively connected to the vent valve, adjusting means arranged for operation by fluid pressure for adjusting the wedge slide and a flexible pipe connected to said space and said adjusting means for displacing the wedge slide and moving the valve into the closing position as the squirting pressure increases the pressure of the fluid in the said space.

15. In a machine for squirting thermoplastic masses, the combination as set forth in claim 4

with a small plate having a spiral track thereon and a tension member passed around said spiral track for supporting the counterweight so as to increase the force exerted by the counterweight on the adjusting means as the wedge slide is displaced to move the valve towards the closing position.

16. In a machine for squirting thermoplastic masses, the combination as set forth in claim 4 with a shaft having a small plate and a gear wheel thereon and adjustable angularly one with respect to the other, the wedge slide having gear teeth thereon meshing with the said gear wheel.

13

EMIL HEMPEL.
